UNITED STATES PATENT OFFICE.

GEORGE H. BARRUS, OF BROOKLINE, MASSACHUSETTS. ASSIGNOR TO INTERNATIONAL PAPER COMPANY, A CORPORATION OF NEW YORK.

TESTING ATTACHMENT FOR STEAM-HEATED DRYING-CYLINDERS.

1,249,886.

Specification of Letters Patent. Patented Dec. 11, 1917.

Application filed September 30, 1915. Serial No. 53,458.

To all whom it may concern:

Be it known that I, GEORGE H. BARRUS, a citizen of the United States, residing at Brookline, in the county of Norfolk and 5 State of Massachusetts, have invented certain new and useful Improvements in Testing Attachments for Steam-Heated Drying-Cylinders, of which the following is a specification, reference being had therein to the 10 accompanying drawing.

In drying apparatus, designed more particularly for drying paper in the manufacture of the same, hollow steam heated rotary cylinders are employed, around which 15 the paper web passes, the heating steam being introduced, usually under pressure, through hollow journals on the cylinders. Such cylinders are usually equipped with means for the discharge of the water of condensation collecting in the lower portion of 20 the cylinder, since any considerable accumulation of the water therein will greatly impair the heating effect of the steam. It is desirable therefore that means be provided 25 to enable the attendant to ascertain if the water is being properly discharged from the cylinder, or has collected therein, and if so, to what extent. It has been proposed, in order to meet these conditions, to apply 30 a try-cock to the head of the cylinder near its outer edge, so that by opening the cock and observing whether the issuing jet blows water or steam, and noting to what angular distance in the revolution of the cylinder the 35 cock blows off water, if any, the amount of water within the cylinder will be revealed. Such an expedient is applicable only to slow running machines, or to those temporarily slowed down for the purpose of applying 40 the test, but in any machine it is objectionable for a number of reasons, mainly because the escaping water striking the frame of the machine, splashes down on the paper web and felt and interferes with the drying 45 action.

My invention aims to enable the attendant to readily determine the conditions obtaining within the cylinder with respect to the discharge of the water or the degree of accumulation therein, without the objections above mentioned, and without the necessity of reducing the speed of operation, and the invention consists in combining with the rotary cylinder, a test pipe having a portion 50 within the cylinder provided with an inlet 55 opening, and having a portion extending outside the cylinder and provided with a vent opening controlled by a valve, the said pipe being movable at will to vary the height of the inlet opening within the cylinder; whereby by opening the vent opening and moving the pipe, the character of the jet issuing through the vent opening, whether steam or water, and the position of the pipe, will reveal to the attendant the 60 conditions within the cylinder.

In carrying my invention into effect in its preferred form, I propose to utilize a known form of siphon drain pipe employed to effect the discharge of water from the cylinder, by so modifying its form and mounting that its function as a drain pipe may be rendered inactive at will, and it may then be operated to act as a test pipe. Such a drain pipe comprises a longitudinal portion 70 extending outside the cylinder and provided with a discharge opening, and a lateral portion within the cylinder provided with an inlet opening, the pressure of steam on the surface of the water of condensation forcing the same up into the lateral portion of the pipe and causing its discharge therethrough. To utilize such form of drain pipe in carrying my invention into effect, I provide the pipe with a valve controlled 75 vent opening, I arrange means for shutting off the normal discharge of the water through the pipe, thereby rendering its discharging function inactive, and I so sustain the pipe that while it may be held 80 fixedly relatively to the rotary cylinder when it is acting as a drain pipe, it may be turned at will about the axis of its longitudinal portion to raise and lower the inlet opening in the pipe within the cylinder. As a result 85 of this construction and arrangement of the parts, by opening the valve controlling the vent opening in the pipe, interrupting the discharge through the normal discharge opening, and by moving the pipe to raise the 90 inlet opening within the cylinder, the attendant can note at what point in the movement of the pipe, the jet issuing from the vent opening begins to blow steam, and can thus determine the height of the water level 95 within the cylinder, and the quantity of water therein. The determination of the water level may be facilitated by applying to the longitudinal portion of the pipe, outside the cylinder, an indicating arm extend-

105

110

ing radially from the pipe in the same relative position thereto as that of the lateral portion of the pipe within the cylinder, so that the position of the arm relative to the 5 head of the cylinder at the moment that the vent opening blows steam, will show accurately the corresponding position of the lateral portion of the pipe within the cylinder, and consequently the water level may 10 be readily determined.

In the accompanying drawings:

Figure 1 is a central longitudinal section through a drying cylinder having my invention embodied therein.

15 Fig. 2 is a longitudinal section on an enlarged scale of the drain pipe and sustaining parts removed from the cylinder, said pipe constructed in accordance with my invention.

20 Fig. 3 is an end elevation of the same.

Fig. 4 is a side elevation showing how the drainage pipe is mounted and operated.

Fig. 5 is a horizontal sectional view on the line $a-a$ of Fig. 4.

25 Referring to the drawings:

1 represents one of a series of rotary hollow drying cylinders employed in paper making machines for drying the damp paper web, and around which cylinders the web is 30 adapted to pass as the cylinders are rotated.

The cylinders are heated internally by the introduction of steam therein, in the present instance the cylinder being provided with a hollow journal 2 projecting axially from the 35 head of the same and mounted in suitable bearings 3, the steam entering the cylinder through said journal. As shown in Fig. 1, the end of the journal abuts steam-tight against a casting or frame 4, which frame is

40 formed with an internal chamber 5, to which a steam supply pipe 6 is connected. A collar 7 extends through the hollow journal and is screwed at its outer end into an opening in the frame, the interior of the collar communicating with the chamber 5 so that the steam entering the pipe 6 will flow through the collar 7 and enter the cylinder. 8 represents a drain pipe for the discharge of such water of condensation as may collect in 45 the lower portion of the cylinder. This pipe is formed with a longitudinal portion 8^a extending centrally through the hollow journal 2 within the collar 7, through the chamber 5 in the frame 4 and outwardly through a

50 stuffing box 9 at the end of the frame. The inner portion of the pipe within the cylinder is bent laterally, and terminates at its end adjacent the inner surface of the cylinder, so that when the lateral end extends 55 downwardly vertically within the cylinder, the inlet opening in its end will be in position to receive the water of condensation. Outward of the chamber 5, the frame 4 is provided with a chamber 10, through which 60

65 the longitudinal portion of the drain pipe

passes, and within this chamber the pipe is formed in its side with a discharge opening 11 through which the water of condensation from the cylinder is discharged and flows into a discharge pipe 12 connected with the 70 chamber 10 and provided with a cut-off valve 13 for the purpose presently to be described.

In the normal operation of the mechanism so far described, the pressure of the steam 75 introduced by the steam supply pipe 6, acting on the surface of the water of condensation within the cylinder, will force the same up into the entrance end of the drain pipe, and the water flowing therethrough will 80 issue through the discharge opening 11 and flow off through the discharge pipe 12, it being understood that the valve 13 remains open in this operation.

In accordance with my invention, the longitudinal portion 8^a of the drain pipe, is so 85 mounted within the frame 4 and collar 7, that the pipe may be turned therein about its longitudinal axis, the result of which will be to raise and lower the inlet end of 90 the laterally extending portion within the cylinder, the stuffing box 9 before alluded to, preventing the escape around the pipe, of water from chamber 10. The outer end of the longitudinal portion of the drain pipe 95 beyond the frame 4 is open, and constitutes in effect a vent opening, which in the normal operation of the pipe as a drain pipe, is closed by a valve 14. The purpose of this vent opening is to indicate to the attendant 100 the presence or absence of accumulated water within the cylinder, and whether or not the water is being properly discharged in the normal operation of the machine. These objects are effected in the following manner: 105 When the attendant desires to be apprised of the conditions mentioned, he first closes the valve 13 in the discharge pipe 12, and then opens valve 14 of the vent opening of the drain pipe, and turns the longitudinal 110 portion of the pipe about its axis, the effect of which will be to swing up the lateral end of the pipe within the cylinder and elevate the inlet opening. If there is accumulated water within the cylinder, water will issue 115 from the vent opening, and will continue to issue until, by the continued turning of the pipe, the inlet opening passes above the water level, whereupon steam will issue through the vent opening. Therefore by 120 noting the point in the movement of the pipe at which the water ceases to flow and steam begins to flow, the attendant will be enabled to calculate the level of the water in the cylinder.

125 In the normal operation of the apparatus, the drain pipe for draining purposes is held in fixed relation to the rotary cylinder, with its inner lateral end extending vertically downward as shown in Fig. 1, so that the in- 130

let opening will be in the lowest position to drain off the water to the lowest level, the pipe being held in this position by releasable locking means, so that the attendant, by releasing these locking means, will be enabled at will, and whenever the test is to be made, to turn the pipe as described. In order that the pipe may be thus held, and may be conveniently turned when desired, and 10 in order that means may be afforded for indicating readily and with accuracy, the level of the accumulated water, I fix to the exposed end of the longitudinal portion of the pipe, a handle 15 which projects radially therefrom, and which, by being applied thereto in the same angular relation as that of the lateral inner end of the pipe, will serve, in addition to an operating handle, as an indicating means for showing on the out- 15 side, the position of the end of the pipe within the cylinder.

As shown more particularly in Figs. 4 and 5, the handle is releasably locked to the frame or casting 4, by means of a horizontal plunger 17 extending loosely through an opening in the handle and through a guiding opening 18 in the frame, so that by withdrawing the plunger outwardly from its guiding opening to disengage the same from 20 the frame, the handle will be free to be moved to turn the drain pipe, and so that when the plunger is seated within its guiding opening and engaged with the frame, the handle will be locked, the relation of the 25 parts being such that when the handle is locked, the inner lateral end of the pipe will extend vertically downward within the cylinder as shown in Fig. 1. The plunger is provided near its inner end with an annular 30 groove 17^a, and is releasably locked within its guiding opening in engagement with the frame to hold the handle locked, by means of a horizontal locking pin 19 mounted to slide loosely in a horizontal opening in the 35 frame 4, in such relation to the annular groove in the plunger, that when the latter is seated to its full extent in its guiding opening, the end of the pin will enter the annular groove, and will lock the plunger in 40 place. The pin is acted on by a leaf spring 21 fixed at one end to the frame 4, and slotted at its opposite end to embrace the pin, the said spring bearing on a shoulder 22 on the pin and acting to hold the pin 45 yielding inward as shown in Fig. 5. The pin is provided with a knurled head 22^a for withdrawing it to disengage its inner end from the plunger, and the plunger is provided on its end with a knurled head 23 by 50 which it may be withdrawn endwise to release the handle after the locking pin has been actuated to release the plunger.

In the operation of the drain pipe for making the tests mentioned, the valve of the dis- 55 charge pipe 12 being closed, and the vent

valve 14 of the drain pipe opened, the handle 15 is released as before described, and is turned to the right, and then to the left, until the flow of water in each position ceases, and the escaping jet changes to steam. 70 These two points mark the angular positions of the entrance end of the pipe within the cylinder when said entrance end is at the water level, and thereby the location of the level of the water is established, and consequently its depth. If in this operation of the drain pipe, neither water nor steam issues through the vent opening, it indicates a stoppage in the pipe, and inasmuch as the pipe extends straight longitudinally from its 80 lateral inner end, a fine wire may be introduced through the vent opening and pushed through the pipe, and the obstruction removed. The introduction of the wire into the pipe is permitted and facilitated by the 85 construction of the valve 14, which as shown in Fig. 4 is provided with a straightway valve passage 14^a; this passage, when the valve is turned to open position, forming a straight continuation of the passage through 90 the pipe. As a result, the wire may be readily entered into and pushed through the valve and pipe without liability of being obstructed by the valve.

In the foregoing description and accompanying drawings, I have set forth my invention in the particular form and embodiment which I prefer to adopt, and which in practice has been found to answer to a satisfactory degree the ends to be attained. It 95 will be manifest, however, to the skilled mechanician, that the invention is not limited to this form of embodiment, and that various changes in the detailed construction of the same may be made without departing from 100 the limits of my invention provided the operation will be substantially as above indicated. Further it will be understood that the invention is not limited to any particular form or construction of the parts except in 105 so far as hereinafter specified in the claims.

Having thus described my invention, what I claim is:

1. In combination with a rotary cylinder having means for the introduction of steam 115 therein, a test pipe having a portion within the cylinder provided with an inlet opening, and having a portion outside the cylinder provided with a vent opening, and a valve controlling said vent opening, so disposed 120 that the jet issuing therefrom will be exposed to view, said pipe being movable at will to vary the height of the inlet opening.

2. In combination with a rotary cylinder having means for the introduction of steam 125 therein, a test pipe having a laterally extending portion within the cylinder provided with an inlet opening, and having a longitudinal portion extending outside of the cylinder and provided with a vent open- 130

- ing, so disposed that the jet issuing therefrom will be exposed to view, a valve controlling the vent opening, and an indicating member fixed to the longitudinal portion of the pipe in the same angular relation thereto as that of the laterally extending portion, said longitudinal portion of the pipe being rotatable about its axis to vary the height of the inlet opening within the cylinder.
10. 3. In combination with a rotary cylinder having means for the introduction of steam therein, a normally fixed pipe for the discharge of the water of condensation therefrom, and means for rendering the discharging function of the pipe inactive at will, said pipe being movable from its normal position while its discharging function is inactive and being provided with a vent opening so disposed that the fluid issuing therefrom will be exposed to view.
15. 4. In combination with a rotary cylinder provided with means for the introduction of steam therein, a normally fixed drain pipe entering the cylinder and through which the water of condensation is normally discharged, said pipe being provided with a valve-controlled vent opening so disposed that the jet issuing therefrom will be exposed to view, and said pipe being movable at will from its normal position to cause the discharge through the vent opening.
20. 5. In combination with a rotary cylinder provided with means for the introduction of steam therein, a normally fixed drain pipe entering the cylinder and through which the water of condensation is normally discharged, said pipe being provided with a valve-controlled vent opening so disposed that the jet issuing therefrom will be exposed to view, and said pipe being movable at will from its normal discharging position for test purposes.
25. 6. In combination with a rotary cylinder having means for the introduction of steam therein, a test pipe having a laterally extending portion within the cylinder provided with an inlet opening, and having a portion outside the cylinder provided with a vent opening so disposed that the jet issuing therefrom will be exposed to view, a valve controlling said vent opening, and a handle applied to the exposed portion of the pipe for turning the same to vary the height of the inlet opening within the cylinder.
30. 7. In combination with a rotary cylinder having means for the introduction of steam therein, a test pipe having a laterally extending portion within the cylinder provided with an inlet opening, and having a portion extending outside the cylinder provided with a vent opening so disposed that the jet issuing therefrom will be exposed to view, a valve controlling said vent opening, a handle on the exposed portion of the pipe for turning it to vary the height of the inlet opening within the cylinder, and releasable means for locking said handle to hold the pipe normally fixed relatively to the cylinder.
35. 8. In combination with a rotary cylinder having means for the introduction of steam therein, a normally fixed drain pipe extending into the cylinder and having an inlet opening, said pipe being movable at will to vary the height of the inlet opening, and being provided with a normally closed vent opening for test purposes so disposed that the fluid issuing therefrom will be exposed to view.
40. 9. In combination with a rotary cylinder provided with means for the introduction of steam therein, a drain pipe having a longitudinally extending outer portion situated outside the cylinder and open at its outer end, and having a laterally extending inner portion with an inlet opening within the cylinder, and having in its longitudinal portion a lateral opening for the normal discharge of the water, a valve closing the outer end of the pipe, means for shutting off the normal discharge of the water through the discharge opening, and means for turning the pipe at will about the axis of its longitudinal portion to vary the height of the inlet opening.
45. In testimony whereof, I have affixed my signature.

GEORGE H. BARRUS.
